Primary Examiner — Jennifer Rivard*Assistant Examiner* — April Rivas(74) *Attorney, Agent, or Firm* — Lieberman & Brandsdorfer, LLC(57) **CLAIM**

The ornamental design for a combination container and wagon, as shown and described.

DESCRIPTION

FIG. 1 is a front perspective view of a combined container and wagon showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines are included for the purpose of illustrating portions of the multi-terrain container that form no part of the claimed design.
